UNITED STATES PATENT OFFICE.

ADAM M. GOODWIN, OF WILKINSBURG, PENNSYLVANIA.

REVERSING MECHANISM.

1,421,213.

Specification of Letters Patent. Patented June 27, 1922.

Application filed August 9, 1920. Serial No. 402,272.

To all whom it may concern:

Be it known that I, ADAM M. GOODWIN, a citizen of the United States, and resident of Wilkinsburg, in the county of Allegheny and State of Pennsylvania, have invented a new and useful Improvement in a Reversing Mechanism, of which the following is a specification.

This invention relates to a reversing mechanism.

For clothes washing machines and the like it is highly desirable that the drum of the machine be rotated and that the direction of rotation be automatically reversed after a single revolution, or after a predetermined number of revolutions in the same direction.

It is also desirable that the reversing mechanism be compact in order to economize in the quantity of grease required for lubrication; that the parts be such as to minimize likelihood of breakage; and that the power transmitting means be smooth in operation and simple to manufacture.

An object of the invention is, therefore, to provide reversing mechanism in which the reversing action is secured by means of a compact gear assembly without calling into play lever or clutch during operation of the mechanism.

A specific object of the invention is to secure the reversal by the direct interaction of an assembly composed of spur gears; such arrangement providing compactness in the elimination of lever arms, smoothness due to the superior meshing qualities of spur gears, and economy due to the elimination of the more expensive bevel gears.

In the accompanying drawings Figure 1 is a side elevation of the reversing mechanism with a portion of its containing housing removed; Figure 2 is a plan view of the mechanism with a portion of the housing removed; Figure 3 is a cross section through the mechanism on the line 3-3; Figure 2; Figure 4 is a cross section through a modified form of the device; and Figure 5 is a vertical section taken on the line 5-5 of Figure 4.

The reversing mechanism of the present invention is preferably contained in a suitable casing 1, which may be filled with grease to lubricate the moving parts of the mechanism. The mechanism illustrated in Figures 1, 2 and 3 of the drawings comprises a shaft 2, mounted in a bearing 3 in the casing and carrying a sheave 4 for connection with a

suitable source of motive power. Shaft 2 carries a pinion 5, which meshes with a gear 6 keyed or splined on the cross shaft 7 mounted in bearings 8 in the casing. Rotatably mounted on shaft 7 is a bracket 9 of oblate U-shape in longitudinal section which carries pinions 10 and 11 on the short shafts 12 and 13, these pinions meshing with a gear 14 normally free on the shaft 7. Keyed or splined on the shaft 7, and arranged to cooperate with the gear 14, is a clutch 15, operable by means of the throw-ing lever 16.

When the device is connected with a source of power, and clutch 15 is in engaging position, gear 14 is rotated to rotate the pinions 10 and 11. It is to be understood that throughout the entire operation of the mechanism the clutch is maintained in engagement with gear 14 to rotate the gear 14 uniformly in one direction.

A power shaft 17 is mounted in bearings 18 in the casing 1, and has keyed or splined thereto a gear 19. Means are provided for causing the gear 14 by its uniform rotation to cause alternate reversed revolutions of the power shaft 17.

Such means comprise a pinion 20 on shaft 21 in the bracket 9 and meshing with the pinion 10 so that pinion 20 and pinion 11 are caused to rotate in opposite directions; and means for causing the pinions 20 and 11 to alternately mesh with the gear 19 to cause reversed single revolutions of the gear 19.

Bracket 9 is free on shaft 7 so that a rotating movement in either direction may be imparted to it. For causing such movement, the gear 19 carries on a face thereof a pin 22 into the path of which projects a nose 23 on the bracket 9. A second nose 24 on the bracket engages in either one of the pockets *a* or *b* in a spring member 25, for holding the bracket in position to engage either the pinion 11 or pinion 20 with gear 19. The spring member 25 is illustrated as formed of a strip of resilient metal, and the edges of the pockets *a* and *b* are so rounded that the nose 24 may be readily forced into or out of either one thereof under a direct impulse imparted to the bracket.

Assuming that the gear 14 is engaged by clutch 15 and is being rotated uniformly in clockwise direction, and that bracket 9 is in position for the nose 24 to engage in pocket *a* of spring member 25; pinion 20, rotated in a clockwise direction by the pin-

ion 10, will cause a single counter-clockwise revolution of gear 17 until the pin 22 strikes the under side of nose 23 on the bracket. This impact causes a rotational movement of bracket 9, causing withdrawal of nose 24 from the pocket *a* of spring member 25 and causing it to enter the pocket *b* therein. In this position, pinion 20 is thrown out of mesh with gear 19, while pinion 11, rotating in a counter-clockwise direction, is thrown into mesh with gear 19 to impart thereto rotation in a clockwise direction. After a single revolution, the pin 22 strikes the upper side of nose 23, rotating bracket 9 and forcing its nose 24 out of pocket *b* and into the pocket *a*. In this position pinion 21 is caused to again mesh with gear 19 to rotate the gear in a counter-clockwise direction.

The modified form of the device illustrated in Figures 4 and 5 of the drawings, is so designed as to produce a reversal of the direction of rotation of the power shaft of the device after a predetermined number of revolutions in either direction.

This form of the device comprises a casing 26, shaft 27, driving sheave 28, pinion 29, shaft 30, and gear 31 on said shaft, generally similar to corresponding elements of the form of the device described above. The bracket 32 is similarly free on the cross shaft 30, and is provided with a relatively stiff helical spring 33 secured to bracket 32 and to the casing 26.

Journalized in casing 26 is the power shaft 34, on which is rigidly mounted a gear 35. Rotatably mounted in bracket 32 are the pinions 36 and 37 meshing with the gear 31. Also rotatably mounted in the bracket 32 is a pinion 38 meshing with pinion 36. In different positions of the bracket, pinions 37 and 38 are respectively brought into mesh with the gear 35 for revolving the power shaft 34.

The means for alternately throwing pinions 37 and 38 into mesh with gear 35 comprise a pin 39 on the back of bracket 32, a pin 40 on a face of gear 35, and a segmental pinion 41 having thereon teeth arranged to project into the path of movement of pin 40 and to contact with pin 39. The segmental pinion 41 is likewise rotatably mounted on bracket 32, and is provided with a number of teeth corresponding to the number of revolutions which it is desired to impart to power shaft 34 between reversals of its direction of rotation.

Assuming that gear 31 is rotating uniformly in a counter-clockwise direction, the pinion 36 will be rotated in a clockwise direction, and the pinion 38, meshing with gear 35, will be rotated in a counter-clockwise direction. The pinion 37 will be rotating idly in a clockwise direction. This action continues until the gear 35 has made a sufficient number of revolutions

to cause the end tooth *c* to come into contact with pin 39 on bracket 32. The tooth *c* contacting with pin 39, due to the rotation of gear 35, causes a rotational movement of the bracket 32, forcing spring 33 past its dead center into the position indicated in dotted lines in Figure 5 of the drawings. This rotational movement throws pinion 38 out of mesh with gear 35 and throws pinion 37 into mesh therewith, so that gear 35 is rotated in a counter-clockwise instead of a clockwise direction.

With the parts in this position, the pinion 41 is rotated back tooth by tooth until the other end tooth *d* comes into contact with pin 39, causing another reversal in the direction of rotation of gear 35 and shaft 34.

Obviously by varying the number of teeth on the segmental pinion 41, the number of revolutions between reversals may be varied up to the limit set by the available space on the toothed segment of the pinion.

The device of the present invention is particularly adapted for use in producing the desirable reversals in the direction of rotation of the drum of a washing machine, because of its compact and economical structure. It also presents advantages for this and other uses in the utilization of spur gears only, and in the fact that such gears operate directly in causing reversals in the direction of rotation without the use of clutch or similar mechanism.

As the device is susceptible of a number of modifications without departing from the spirit of the invention, only those limitations contained in the appended claims are to be imposed upon the scope of the invention.

What I claim is:

1. Reversing mechanism comprising a driving shaft, a gear on said shaft, a movable bracket, a pair of driving pinions on said bracket and actuated in mutually opposite directions by said driving gear, a driven shaft, a gear thereon, and means on said driven gear arranged to contact with and shift said bracket for alternately engaging each of said pinions with said driven gear.

2. Reversing mechanism comprising a movable bracket, a pair of driving pinions on said bracket, a driving shaft, means on said driving shaft for rotating said pinions in mutually opposite directions, a driven shaft, and means on said driven shaft for causing said pinions to alternately impart motion thereto.

3. Reversing mechanism comprising a movable bracket, a pair of driving pinions on said bracket, means on said driving shaft for rotating said pinions in mutually opposite directions, a driven shaft, a gear on said driven shaft, and means on said gear for bringing the pinions on said bracket alter-

nately into mesh with said driven gear to impart motion in reversed directions to said driven shaft.

4. Reversing mechanism comprising a driving shaft, a gear on said shaft, a movable bracket, a pair of driving pinions on said bracket and actuated in mutually opposite directions by said driving gear, a driven shaft, a gear thereon, means on said driven gear arranged to contact with and shift said bracket for alternately engaging each of said pinions with said driven shaft, and resilient means arranged to hold said bracket stationary between positive actuations thereof.

5. Reversing mechanism comprising a movable bracket, a pair of driving pinions on said bracket, a driving shaft, means on said driving shaft for rotating said pinions in mutually opposite directions, a driven shaft, means on said driven shaft for shifting said bracket and causing said pinions to alternately impart motion thereto, and resilient means arranged to hold said bracket stationary between positive actuations thereof.

6. Reversing mechanism comprising, a driving shaft, a movable bracket, a pair of driving pinions on said bracket, means on said driving shaft for rotating said pinions in opposite directions, a driven shaft, a gear on said driven shaft, means on said gear for bringing the pinions on said bracket alternately into mesh with said driven gear to impart motion in reversed directions to said

driven shaft, and resilient means arranged to hold said bracket stationary between positive actuations thereof.

7. Reversing mechanism comprising a driving shaft, a gear on said shaft, a movable bracket, a pair of driving pinions on said bracket and rotated in opposite directions by said driving gear, a driven shaft, a gear thereon, a protuberance on said bracket, and a member on said driven gear arranged to contact with said protuberance and shift said bracket for bringing the pinions on the bracket alternately into mesh with the driven gear.

8. Reversing mechanism comprising a driving shaft, a gear on said shaft, a movable bracket, a pair of driving pinions on said bracket and rotated in opposite directions by said driving gear, a driven shaft, a gear thereon, a protuberance on said bracket, a member on said driven gear arranged to contact with said protuberance and shift said bracket for bringing the pinions on the bracket alternately into mesh with the driven gear, and resilient means arranged to hold said bracket stationary between positive actuations thereof.

In witness whereof, I hereunto set my hand.

ADAM M. GOODWIN.
